UNITED STATES PATENT OFFICE.

EDWIN NORTON, OF MAYWOOD, ILLINOIS, ASSIGNOR TO THE NORTON BROS., OF CHICAGO, ILLINOIS.

SHEET-METAL-SEAMING MACHINE.

SPECIFICATION forming part of Letters Patent No. 610,558, dated September 13, 1898.

Application filed October 7, 1897. Serial No. 654,334. (No model.)

To all whom it may concern:

Be it known that I, EDWIN NORTON, a citizen of the United States, residing in Maywood, in the county of Cook and State of Illinois, have invented a new and useful Improvement 5 in Sheet-Metal-Seaming Machines, of which the following is a specification.

My invention relates to sheet-metal-seaming machines intended for seaming the covers on sheet-metal cans, and more particularly to certain improvements upon the machine shown and described in Letters Patent No. 546,468, granted to F. E. Heinig September 17, 1895.

15 The object of my invention is to improve and perfect said machine and increase its capacity, so that the work may be done more perfectly, rapidly, and cheaply.

With this object in view I combine with a 20 clamping-ring made in two or more opening-and-closing parts (and herein my invention consists) mechanisms for automatically opening and closing the parts of said clamping-ring, a revolving sleeve or frame furnished 25 with antifriction rollers or wheels adapted to travel on the upper edge of said clamping-ring, and seaming-rollers journaled on operating-levers pivoted to said sleeve or frame and operated by a reciprocating block or head 30 to press the seaming-rollers against the can-head flange into operative position. The opening-and-closing parts of the clamping-ring may be produced in any suitable manner; but I prefer to form them not by dividing 35 the clamping-ring into two or more opening-and-closing segments, but simply by cutting or splitting the clamping-ring at one point, so that the opening and closing of the clamping-ring to receive, clamp, and release 40 the can may be effected simply by separating or drawing together the two meeting ends of the split ring.

My invention further consists in the novel construction of parts and devices and in the 45 novel combinations of parts and devices herein shown and described and forming the subject of the claims herein.

In the accompanying drawings, forming a part of this specification, I have illustrated at 50 Figures 1, 2, 3, 4, 5, and 6 a machine embodying my invention, Fig. 1 being a side eleva-

tion, Fig. 2 a central vertical section, Fig. 3 a detail back end elevation, Fig. 4 an enlarged detail sectional view taken at right angles to the section of Fig. 2, Fig. 5 a detail elevation 55 of the mechanism for opening and closing the split clamping-ring, Fig. 6 a detail plan of the split clamping-ring. Fig. 7 is a sectional view of the can and cover after being seamed by the machine, and Fig. 8 is a detail plan-view 60 of the clutch.

In said drawings, A represents the frame of the machine, and B the opening-and-closing up-and-down-reciprocating clamping-ring, the opening-and-closing parts of which are 65 preferably formed, as before stated, by splitting the ring at one point b of its circumference. The cut or slit b across the clamping-ring is preferably an angular or V-shaped cut, so that the parts of the ring will better 70 register with each other when forced together. To give the ring B its up-and-down reciprocating movement to enable it to be brought down over the mouth of the can X and removed therefrom, it is mounted upon a vertically-reciprocating slide, yoke, or frame C, that moves up and down in suitable guides C' on the frame of the machine. The clamping-ring B is provided at opposite points of its circumference with projecting arms B', connected to the reciprocating slide C. The two separate meeting ends or parts of the opening-and-closing clamping-ring B may be automatically forced together or separated to clamp or release the can by any suitable 75 mechanism, but preferably by means of a lever D, connected by a pivot d to one of the meeting ends B' of the clamping-ring and which is furnished with an incline or cam-slot d', that engages a pin or projection d² on 80 the other meeting end B' of the clamping-ring. The lever D is preferably pivoted to the frame of the machine at d³ by a pivot-pin d⁴, carried by a bracket d⁵, that is attached to the frame and is automatically operated to open and close the clamping-ring B by the reciprocating or up-and-down movement of the clamping-ring itself.

F F are the seaming-rollers, the same being preferably four in number, although a greater or less number may be employed. These seaming-rollers are journaled upon

movable levers or arms F' , which are connected by pivots f to ears g on a revolving ring or sleeve G , which serves to rapidly revolve the seaming-rollers around the axis of said ring and inside the clamping-ring B . The seaming-rollers F are forced out against the flange x of the can-cover X' by means of a reciprocating operating-head H , which is furnished with an annular groove h , in which fit the inner arms f' of the seaming-roller-carrying levers F' . The ring or sleeve G is provided with antifriction-rollers g' , that travel upon the upper edge b of the opening-and-closing clamping-ring B . The arms B' on the clamping-ring B are provided with holes b' , through which pass the guide-pins c on the yoke or bracket C^2 , secured to and forming part of the slide C , so that the slide may have a slight up-and-down movement independent of the clamping-ring limited by the nuts c' on said pins c .

The rotating ring or sleeve G is splined to and rotated by a rotating shaft G' , journaled in suitable bearings G^2 on the frame of the machine and G^3 on the slide C . The seaming-roller-operating head H is secured fast to the shaft G' and moves up and down with it. The shaft G' is furnished with a collar g^2 , that engages the slide C , so that the shaft G' and the head H will be forced down by the movement of the slide. A coil-spring G^4 is inserted between the sleeve or ring G and a shoulder g^2 on the shaft G' , so that said ring G will be forced down with the shaft G' , while permitting the ring G to be lifted or raised by the clamping-ring B independently of the head H and shaft G' .

The slide C is automatically moved up and down as required by means of a cam K on the shaft K' through a connecting-lever K^2 , pivoted at K^3 to the frame and having a slotted connection K^4 with the slide C . The lever K^2 may be provided with a treadle-arm K^5 to enable the slide to be operated by the foot, if desired.

M is the driving-shaft, around a pulley m on which a belt m' passes to a pulley G^5 on the shaft G' to rotate the same.

Motion is communicated to the cam-shaft K' from the driving-shaft M through a pulley m^2 on said shaft, belt m^3 , and pulley m^4 on counter-shaft m^5 , which is furnished with a gear m^6 , that meshes with a gear m^7 , loose on the shaft K' , and which is provided with a clutch member m^8 , that is engaged by a sliding clutch pin or member m^9 on the clutch sleeve or collar m^{10} , that is fast on the shaft K' . After the shaft K' makes one complete revolution the sliding pin or clutch member m^9 is withdrawn from the clutch member m^8 by a cam-lever m^{11} , pivoted to the frame at m^{12} , and which is connected by a link m^{13} with the clutch-operating hand-lever m^{14} .

P is the lower chuck-disk, upon which the can X rests while being operated upon. It is mounted upon an adjustable slide P' , that can be set in any position desired to accom-

modate different sizes of cans by the adjusting-screw P^2 .

The operation of the machine is as follows: The can X being placed upon the chuck-disk P , the operator moves the clutch-lever m^{14} with his hand, thus raising the clutch cam or lever m^{11} and permitting the two parts or members of the clutch to engage, thus giving the cam K one revolution, and thereby automatically moving the slide C down until the opening-and-closing clamping-ring B surrounds the upper end of the can, as illustrated in Fig. 4, at which time the opening-and-closing parts of the clamping-ring are automatically closed or clamped around the can by the action of the cam-lever D , and then the further downward movement of the slides C and the shaft G' forces the seaming-rollers F into position against the flange x of the can-cover, thereby seaming the cover on the can, as illustrated in Fig. 7. The further rotation of the cam K causes the slide C to withdraw, the first operation of the withdrawal being to lift the head H and the ring or sleeve G , and thus release the can from the pressure of the seaming-rollers, and then to open and lift the clamping-ring from the can. When the cam K finishes its revolution, its shaft K' is automatically disengaged from the driving-gear by the opening of the clutch through the agency of the cam-lever m^{11} , and then another can may be placed in the machine and the operation repeated.

I claim—

1. In a machine for seaming covers on cans, the combination with an opening-and-closing clamping-ring, with mechanism for automatically closing the clamping-ring, seaming-rollers, and mechanism for automatically operating the seaming-rollers, substantially as specified.

2. In a seaming-machine, the combination with an opening-and-closing clamping-ring, mechanism for automatically closing the clamping-ring, seaming-rollers, operating arms or levers upon which the seaming-rollers are journaled, a rotating ring or frame to which the seaming-roller levers are pivoted, and a reciprocating head for operating said seaming-roller levers, substantially as specified.

3. In a seaming-machine, the combination with an opening-and-closing clamping-ring, mechanism for automatically closing the clamping-ring, seaming-rollers, operating arms or levers upon which the seaming-rollers are journaled, a rotating ring or frame to which the seaming-roller levers are pivoted, a reciprocating head for operating said seaming-roller levers, and a reciprocating slide and shaft, substantially as specified.

4. In a seaming-machine, the combination with an opening-and-closing clamping-ring, mechanism for automatically closing the clamping-ring, seaming-rollers, operating arms or levers upon which the seaming-rollers are journaled, a rotating ring or frame to

which the seaming-roller levers are pivoted, a reciprocating head for operating said seaming-roller levers, and a reciprocating slide and shaft, said reciprocating slide being connected to said clamping-ring and having a slight independent reciprocating movement thereon, substantially as specified.

5. In a seaming-machine, the combination with an opening-and-closing clamping-ring, mechanism for automatically closing the clamping-ring, seaming-rollers, operating arms or levers upon which the seaming-rollers are journaled, a rotating ring or frame to which the seaming-roller levers are pivoted, a reciprocating head for operating said seaming-roller levers, a reciprocating slide and shaft, a cam and connecting mechanism for reciprocating said slide, said connecting mechanism being provided with a clutch and mechanism for disengaging the clutch after each rotation of the cam, substantially as specified.

6. In a seaming-machine, the combination with a bodily-reciprocating split opening-and-closing clamping-ring adapted to receive and surround the upper end of the can-body, of a cam-lever D pivoted to one end of the split ring and engaging a pin or projection on the other end of the split ring for closing the same, and a chuck-disk for the can to rest upon, substantially as specified.

7. In a seaming-machine, the combination with an opening-and-closing reciprocating clamping-ring, of an operating-lever for closing the ring pivoted at one end to the stationary frame of the machine and connected

at its other end to the meeting ends of the clamping-ring so that the ring may be automatically closed or opened by the reciprocating movement of the ring itself, substantially as specified.

8. In a seaming-machine, the combination with an opening-and-closing reciprocating clamping-ring, of an operating-lever for closing the ring pivoted at one end to the stationary frame of the machine and connected at the other end to the meeting ends of the clamping-ring so that the ring may be automatically closed or opened by the reciprocating movement of the ring itself, and seaming-rollers and mechanism for operating the same, substantially as specified.

9. In a seaming-machine, the combination with an opening-and-closing reciprocating clamping-ring, of an operating-lever for closing the ring pivoted at one end to the stationary frame of the machine and connected at the other end to the meeting ends of the clamping-ring so that the ring may be automatically closed or opened by the reciprocating movement of the ring itself, and seaming-rollers and mechanism for operating the same, substantially as specified.

EDWIN NORTON.
